IGNITION SYSTEM

Maurice A. Rudd, North Plainfield, N. J., assignor
to Bendix Aviation Corporation, New York,
N. Y., a corporation of Delaware

Application August 29, 1945, Serial No. 613,318

20 Claims. (Cl. 123—148)

1

This invention relates to electrical apparatus and more particularly to an electrical control system adapted for use in controlling the ignition system for one or a plurality of aircraft engines.

One of the objects of the present invention is to provide a control circuit and means for effecting control of the ignition circuit of an engine or the like from a remote position.

Another object is to provide a control system of the above character which provides safety, particularly in combat aircraft.

Still another object of the invention is to provide a simple yet effective means for controlling a large number of circuits such as ignition circuits from a remote position and in certain selected combinations.

Another object is to provide novel remote control means for one or a plurality of electrical circuits whereby the number, length and weight of electrical leads is minimized and the space requirements are cut.

Another object is to provide an electrical control system for the ignition circuit of an internal combustion engine or other electrical instrumentality which is not required to be shielded to prevent interference with radio receiving apparatus.

Another object is to coordinate a master circuit such as that disclosed in this application with particular instruments adapted for use therein such as are disclosed in co-pending applications Serial Nos. 613,317 and 613,318, filed August 29, 1945.

The above and further objects and novel features of the invention will more fully appear from the following detailed description when the same is read in connection with the accompanying drawings. It is to be expressly understood, however, that the drawing is for the purpose of illustration only, and is not intended to define the limits of the invention, reference for this latter purpose being had primarily to the appended claims.

The single figure of the drawing is a diagrammatical representation of a master circuit of the type described, operable from a remote distance through a small number of wires by master or control switches indicated generally by numerals 10 and 64, which operate ignition or relay switches, indicated generally by numerals 11 and 66, that are connected by appropriate leads 12 and 62 to a plurality of magneto coils, only one of which has been shown, it being understood

that each of the other leads is similarly connected.

The apparatus described in application Serial No. 613,318 is adapted for use in place of switch 10 and the apparatus described in application Serial No. 613,317 is adapted for use in place of switch 11, it being understood that those inventions are not limited to use with this invention although they contribute to its success.

The control system illustrated diagrammatically and by way of example in the accompanying drawings is one adapted for use in controlling the operation of the ignition circuits of all four engines of a four-engine aircraft, each of which is equipped with seven dual type magnetos having two coils operating through separate circuits to supply current through separate distributors to one bank of spark plugs of one row of a multi-row engine. In systems of this type the right-hand coil in a magneto serves the right-hand bank of spark plugs in one cylinder row and the left-hand coil serves the other bank of spark plugs in the same row of cylinders. In aircraft having four engines, the engines are necessarily mounted at a substantial distance from the pilot's cabin and from the flight engineer's control panel so that the usual control means for the ignition systems thereof requires the use of a large number of long conductors, the very weight of which is objectionable and the length of which increases their vulnerability and the vulnerability of the airplane. Furthermore, all such leads are prospective sources of radio leakage and interference and frequently require radio shielding which adds objectionable weight to what is already too heavy.

For the purpose of illustration, one side of one magneto, and a complete control system for one engine are shown. The systems for all engines are identical with that illustrated. Each magneto has a left coil consisting of a primary winding 15 and a secondary winding 16, the former of which is connected in circuit with a cam operated circuit breaker 17 and a condenser 18 in the usual manner. The secondary winding 16 is connected through a distributor 19 with a plurality of spark plugs 20, the number of which corresponds to the number of cylinders in the cylinder row. It will be understood by mechanics that the system is as applicable to engines having only one cylinder per row as to those having a plurality thereof. Each magneto contains coils and circuits in which electrical energy is generated in a known manner by a single magneto rotor or equivalent means which are not shown.

One end of the primary winding 15 is permanently grounded at 21 and provision is made through a switch 23 whereby the other end of said primary coil may be grounded. It will be readily understood by persons skilled in the art that when both ends of the primary coil are grounded the magneto coil is inoperative and no energy is furnished at the spark plug. In the usual system this is accomplished by manually closing an ignition switch. In the present installation, the purposes of the invention are accomplished by novel circuits and remote control wherein the left-hand bank of spark plugs may be affected in co-ordination with the right-hand bank so that one or the other bank may be separately tested.

A novel relay or operating switch 11, so-called to distinguish it from the novel master or control switch 10, has stationary contacts 22 each of which is connected by a lead 12 to one of the primary coils 15 of one of the seven magnetos of an engine. Movable element 23 of the ignition switch is illustrated as being semi-circular and having contact brushes 24 on the curved perimeter thereof that are adapted for simultaneous engagement with contacts 22. The brushes 24 may be connected to ground as at 25 in any suitable manner such as through armature member 26 and the pivotal mounting thereof. The said member 23 is provided with a suitable armature 26 in operative relation to a plurality of electromagnets 27 and 28. The contacts 22 and 24 are closed by magnet 27 by throwing the armature and the member 23 in a clockwise direction about a pintle 29. The electromagnet 28 moves the brushes 24 out of engagement with the contacts 22 by throwing the armature 26 in the reverse direction. The armature 26 may be yieldably held in each of its two extreme positions by any suitable means such as a cam faced pivoted latch 30 which is held in engagement with the armature by means of a spring 31, and the cams of which are engageable with opposite sides of the armature and hold the member in a selected position. The effect of spring 31 and the cams on lever 30 is less than the effect of the magnet 27 or 28 so that the energizing of the proper magnet will always throw the switch and will not be prevented by the lever.

Novel simplified means which insure maximum safety are provided for energizing the coils of the electromagnets 27, 28 to effect the desired operation of switch member 23. As shown, one end of coil 27 is connected through a lead *a* to ground at 40 and one end of coil 28 is connected by a lead *b* to the ungrounded terminal of a source of electrical energy such as a battery 41 through a bus line *c* which may extend through both wings and the fuselage of the aircraft. The other terminals of coils 27 and 28 are connected to resilient or movable switch arms 42 and 43, respectively, which are adapted to alternately contact a central contact arm 44. The alternate connection is effected by an actuating arm 45 connected to armature 26. When the latter is in the illustrated position, the arm engages spring 42 holding it out of contact with central arm 44 and permitting spring arm 43 to make contact therewith. When armature 26 is moved to its other position, spring 42 is permitted to contact arm 44 and spring 43 is moved out of contact therewith. Both arms 42 and 43 are normally biased toward engagement with arm 44.

Switch arm 44 is connected by a control wire *d* to a terminal 50 of the control switch 10, which is usually located on the flight engineer's control

panel. Terminal 50 is adapted to be connected with any one of four contacts or switch points O, R, L or B through a pivoted lever 51. During normal operating conditions, contacts B and L are connected to ground through lead *e*, an emergency switch 60, a lead *f* and a second emergency switch 61. Any number of such emergency switches may be provided for simultaneously making all engines inoperative. Contacts R and O are connected to bus line *c* through lead *g* and thence to the source 41 of electrical energy.

The emergency switch 61 is a simple, two-position switch; when it is in "on" position it connects terminals of the control switch 10 to ground and when it is in "off" position it connects the same terminals to the source of energy 41 through lead *g* and bus line *c*.

In the novel system that is thus described, there is provided engine ignition control wherein the application of ground to a relay switch causes it to turn the engine on, and application of battery to the relay switch causes it to turn the engine off. This statement, although true, is deceptive in its simplicity because the conceptions that were required to attain this simplicity, and the mechanism that accomplishes it, are complex.

As shown in the drawing, the switch 61 is in the "on" position, the switch 60 is in the "on" position, the switch 51 is connected to switch point R, switch contacts 43 and 44 are engaged and switch elements 22 are engaged with switch elements 22. Under these circumstances, the battery is connected through lead *b* to coil 28, contacts 43 and 44, lead *d*, switch arm 51, point R and lead *g* to the bus line *c* at *c'*. Therefore, both sides of coil 28 are connected to power and the coil is not energized. Inasmuch as the switch points 44 and 42 which control coil 27 are held open by arm 45 attached to armature 26, coil 27 is also not energized. If the engineer moves the switch arm 51 to point L, current will flow from battery 41 through lead *b* to coil 28, through switch arms 43, 44, switch 51 and point L to line *e* where it passes through switches 60 and 61 to ground, completing the circuit and energizing coil 28 which attracts the armature and throws the switch brushes 24 out of engagement with contacts 22. As soon as the relay switch has operated, the buffer on the end of arm 45 engages the contact 43 and moves it out of engagement with contact 44, breaking the circuit and de-energizing the coil 28. In this new position the coil 27 is connected through the lead *a* to ground at 40 and through lead *h* to arm 42 which is now in engagement with contact 44, lead *d*, contact 51, point L, lead *e*, switch 60, lead *f*, and switch 61 to ground. Both sides of coil 27 are consequently connected to ground and that coil is also not energized. By this means current is turned off in each instance as soon as the relay has operated, so that energy is used only during activation of a coil.

The bus line *c* and lead *g* constitute a power line; the line *e*, *f* constitutes a ground line. It will be observed that the points O and R of switch 10 are connected to the power line and the points L and B are connected to the ground line. Thus, the contact 44 will be connected to ground whenever the switch 51 is in engagement with either point L or B and with power whenever the switch 51 is connected with points R and O. Since the contact 44 is always in engagement with coil 27 or coil 28 through the contacts 42 or 43, respectively, the coil thus contacted will also be connected to ground or power as the case may be.

Therefore, it is the connection of coil 28 to ground which makes the engine operative and the connection of coil 27 to power which makes it inoperative.

It is frequently desirable to cut out one bank of plugs in order that tests may be run on the other bank. In order to accomplish this, a separate circuit substantially identical with that which has been described is provided for the right-hand banks of plugs. The system which has just been described is lettered L and shows seven leads 12 going to the seven coils that serve the left-hand banks of plugs. Similarly, seven leads 62 go to the coils that serve the right-hand banks of plugs and are similarly controlled by a relay switch 63 which is connected through a switch 42R, 43R, 44R and lead d' to switch 64 which also has four contact points O, R, L and B which differ from contact points O, R, L and B of switch 10 in that point R is connected to the ground line and L to the battery line. The switch arms 51 and 65 are connected by a rack 53 which is operated by a pinion 52 as shown so that the two circuits may be controlled simultaneously. When both switch arms 51 and 65 are in engagement with points O both relay switches are thrown so that the switch points are in engagement and all the coils are grounded. When the switch arms 51, 65 are in the position R the left coils are grounded and the right coils are in operation, as shown in the drawings. When switch arms 51, 65 are in engagement with points L the left-hand coils are operating and the right-hand coils are grounded. When arms 51, 65 contact points B both sets of coils operate.

It will be observed that one side of each magnet coil 27, 27R is connected to ground, and that the other side is connectible through the relay switches and switches 10, 64 either to ground or to power. When that connection is to ground, the circuit will extend from ground to ground and no current will flow to energize these magnets, but that when the connection at switches 10 or 64 is to a power source, current will flow from power source to ground and the magnet in circuit will be energized.

Similarly, one side of each magnet 28, 28R is permanently connected to a source of power such as battery 41, and the other side is connectible through the switches to power source or to ground. When the connection is to power source the circuit will extend from power source to power source and no current will flow to energize the magnet, but when connection is to ground the magnet will be energized.

A substantial advantage of the foregoing conception is that power is used only momentarily and is immediately turned off as soon as the selected magnet has functioned.

If desired, a source of power may be made to supply booster current through lines 11, as more fully described in one said co-pending application. Three other pairs of coordinated switches II, III, IV may be made to control similar circuits for three other engines, and their connections to the ground and bus lines are indicated so that the invention may be readily applied by persons skilled in the art to four-engined planes.

In this system, the relay switches are located in close proximity to the engine so that the fourteen lead lines are short, can be well protected without adding objectionable weight and offer a minimum of length exposed to enemy action or accidental injury.

If the flight engineer wishes to turn off all the

engines at once he pulls the switch 60 which allows the center spring 12, which is biased toward contact 73, to break from contact 74 and engage the contact 73. When this is done, all relay switches throw their contacts into engagement with the coil-connected contacts so that all coils are immediately grounded and the engines stop for lack of spark. Similarly if the pilot wishes to stop all the engines he may throw the switch 61 into the "off" position producing a similar result.

Switch 60 can be omitted by connecting leads e and f, and switch 61 can be omitted by connecting contact 74 to ground.

An advantage of the invention is in saving the weight of long leads. Another advantage of the invention is in the relative simplicity of the panel mounted apparatus. Another advantage is in making the right and left banks of plugs in each engine separately available for testing. Another advantage is in each of the means and methods that have been invented to accomplish the manifold and complex conceptions involved in this invention. A further advantage is in the coordination of the parts of two or more complex electrical systems and the reduction of the complexity of control to the simple operation of a dial or a handle.

It will be perceived by engineers that the invention has many uses and that the specific use, while comprehending great novelty in itself is only illustrative. The system composed of switch 10 and switch 11 is adaptable to the remote control of many instrumentalities and the system comprised of switches 10 and 64 and the relay switches 11 and 66 to which they are connected is adaptable to the coordination of other electrical instrumentalities.

While only one embodiment of the present invention has been illustrated and described in detail, it is to be expressly understood that the same is not limited to said embodiment. Various changes may be made in the materials suggested and in the design and arrangement of the parts illustrated without departing from the spirit and scope of the invention, as will now be clear to those skilled in the art. For a definition of the limits of the invention, reference is had primarily to the appended claims.

What is claimed is:

1. Control means for an ignition system or the like comprising a plurality of coordinated switches adapted to be energized and grounded oppositely or together, a plurality of movable means adapted by motion to control a plurality of instrumentalities, a plurality of means connected to said plurality of switches and adapted to move said movable means whereby the movement thereof may be controlled and coordinated by said coordinated switches.

2. Control means for an ignition system or the like comprising a power source and a ground connection, a pair of switches having coordinated means adapted to connect said switches together or oppositely to power and ground, and a pair of relay switches adapted to be connected with said switches and to power and ground in accordance with the setting of the said switches.

3. A means of control for an ignition system or the like comprising a power source and a ground connection, a pair of switches having points similarly connected to power and to ground and points oppositely connected to power and ground and having a pair of coordinated contacts adapted to engage said points and to be

connected respectively with a pair of relay switches, whereby said relay switches may be simultaneously or oppositely connected to power and ground.

4. In apparatus of the type described a set of magneto coils adapted to be rendered inoperative by connection to ground, a second set of magneto coils adapted to be simultaneously electrically affected, switch means to affect said first set comprising a relay, switch means to affect said second set comprising a relay, a source of power, a ground connection, means to control the switch operating means of the relays comprising a pair of switches having a plurality of points connected with ground, a plurality of points connected with power and contacts connected with said relays adapted to be selectively engaged with said points, and means to coordinate said contacts with said points whereby to simultaneously or alternately energize the relays and through said switch means to affect said coils.

5. An ignition system for an engine comprising a plurality of transformer coils adapted to supply a plurality of spark plugs, a relay switch adapted in one position to render said coils ineffective and thereby turn the engine off and in another to render the coils effective and thereby turn the engine on, means to apply ground to the switch whereby to turn the engine on, and means to apply battery to the switch whereby to turn the engine off.

6. An ignition system comprising a plurality of electrical instrumentalities adapted to be made operative or inoperative simultaneously, control switch means adapted to be connected with a power supply or with ground, and means made operative by the said connection to power to make said instrumentalities inoperative and by said connection to ground to make them operative.

7. In apparatus of the type described a set of magneto coils adapted to be made inoperative by connection to ground, another set of magneto coils adapted to be made inoperative by connection to ground, a relay switch adapted in one position to connect one said set to ground, a relay switch adapted in one position to connect another said set to ground, a power line and a ground line, means to coordinate the operation of said relay switches whereby to ground said coils alternately or together comprising switch points connected with the power line, switch points connected with the ground line, and switch contacts connected with the relays and adapted to be simultaneously or alternately connected with said power and ground connected points.

8. In apparatus of the type described a set of magneto coils adapted to be made inoperative by connection to ground, another set of magneto coils adapted to be made inoperative by connection to ground, a relay switch adapted in one position to connect one said set to ground, a relay switch adapted in one position to connect another said set to ground, a power line and a ground line, means to coordinate the operation of said relay switches whereby to ground said coils alternately or together comprising switch points connected with the power line, switch points connected with the ground line, switch contacts connected with the relays and adapted to be simultaneously or alternately connected with said power and ground connected points, and means to simultaneously throw all relay switches to grounding position.

9. Remote control switch means comprising a

plurality of electromagnets, an armature adapted to be thrown by said magnets, switch means adapted to be operated by said armature, and means to energize said magnets alternately comprising a switch, means to connect the switch to a source of energy or to ground and means to connect the switch to a selected magnet.

10. Remote control means comprising a plurality of electromagnets, an armature adapted to be thrown thereby, and means to selectively energize said magnets comprising a relay switch and a remote control switch connected therewith and adapted to selectively connect said relay magnets to power and to ground.

11. Remote control means comprising a plurality of electromagnets, an armature adapted to be thrown thereby, one side of each electromagnet being connected with a switch, the other side of one electromagnet being connected to ground, and the other side of the other electromagnet being connected to power, switch means adapted with said switch to complete a circuit through a said magnet, and means to deactivate the said magnet after it has been energized.

12. Remote control means comprising a plurality of electromagnets, an armature adapted to be thrown thereby, means connecting one side of each said magnet with a switch, means connecting the other side of one said magnet with power, means connecting the other side of the other said magnet with ground, and switch means adapted with said switch to complete a circuit through a said magnet whereby to throw the armature.

13. Remote control means comprising a plurality of armatures, a plurality of electromagnets adapted to operate said armatures connected to ground, a plurality of electromagnets adapted to operate said armatures connected to power, a plurality of switch means completing the connections to said magnets, and means to operate said armatures in selected combinations comprising means to connect said magnets through said switches in selected combinations to power and to ground.

14. Remote control means comprising a source of electrical energy, one terminal of which is connected to a power line and the other terminal of which is connected to ground, a relay mechanism comprising an armature, a pair of electro-magnets adapted to be alternately energized by said source for actuating said armature, one terminal of one said magnet being connected to said power line and one terminal of the other said magnet being connected to ground, and a relay switch means controlled by said armature and comprising a separate contact electrically connected to the other terminal of each of said magnets and a common terminal alternately engageable by said separate contacts to alternately close a connection to one of said magnets while breaking a connection to the other magnet, and a control switch means for selectively connecting said common terminal of the relay switch means to the power line or to ground.

15. Remote control means as defined in claim 14 including switch means operable by said armature for alternately opening and closing at least one electrical circuit containing an electrical instrumentality.

16. Remote control means as defined in claim 14 comprising other switch means for selectively connecting at least one terminal of said control switch means to ground or to the power line.

17. Remote control means as defined in claim 14 comprising a plurality of relay mechanisms

and a control switch means for each of said mechanisms.

18. Remote control means as defined in claim 17 comprising other switch means for selectively connecting at least one terminal of each of said control switch means simultaneously to ground or to the power line.

19. Remote control means as defined in claim 14 comprising at least two of said relay mechanisms and wherein said control switch means comprises at least two coordinated switches for selectively connecting the common terminals of the relay switch means simultaneously to ground, simultaneously to the power line, or either one to ground and the other to the power line.

20. Remote control means as defined in claim 19 comprising other switch means for simultaneously connecting selected terminals of both said

coordinated switches either to ground or to the power line.
